UNITED STATES PATENT OFFICE.

FRANK E. GETTS, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS.

LOCKING-SWITCH.

1,339,506.

Specification of Letters Patent. Patented May 11, 1920.

Application filed February 25, 1918. Serial No. 219,094.

To all whom it may concern:

Be it known that I, FRANK E. GETTS, a citizen of the United States, residing at Chicago, in the county of Cook and State 5 of Illinois, have invented a certain new and useful Improvement in Locking-Switches, of which the following is a full, clear, concise, and exact description, reference being had to the accompanying drawings, forming a part of this specification.

My invention relates to locking switches, and more particularly to locking mechanism for electrical disconnect switches for use in power houses, substations and the 15 like.

It is common practice to provide switches of the above description with locking mechanism for locking the movable switch member in either open or closed positions.

20 The locking mechanism is provided to prevent the switch accidentally moving from its desired position, as might result from vibration of the switch supports or insecure contact between the movable switch 25 member and the switch terminals, or from a heavy flow of current.

Moreover, this locking mechanism necessitates a deliberate premeditated act on the part of the attendant. All of this is to the 30 end of safeguarding expensive transformers and other electrical equipment on the circuit which might be damaged and to protect linemen and substation operators at work repairing the line, replacing blown fuses 35 and such.

The switch is operated by a hook mounted on a pole of wood or like insulation. This hook engages the locking mechanism and releases the same prior to operating the 40 switch. In the switch heretofore constructed, the arrangement of the locking mechanism is such that the action of first releasing the locking mechanism and then operating the switch is accomplished by one 45 movement of the operating pole in a direction in the place of operating movement of the switch. That is to say, the pole is pulled in only one direction, the first part of its movement releasing the locking mechanism

and the latter part of its movement actuating the switch.

The particular objection to this mode of operation is that the operator is pulling against the locking mechanism at the same time that he is trying to release it. As a result 55 the locking parts tend to bind and are withdrawn with difficulty from locking engagement with the switch terminals. Furthermore, in closing the switch the pressure of closing often binds the lock or in some 60 structures releases it.

In my improved locking switch, I have arranged the locking mechanism so that the releasing movement thereof is at an angle or sidewise from the operating movement 65 of the switch. Thus the release of the locking mechanism is effected by movement of the operating pole in one direction and the operation of the switch is effected by movement of the pole in another direction. By 70 this arrangement the releasing movement of the locking mechanism is always at an angle to the direction of locked position of the switch and thus there is less tendency 75 for the locking parts to bind.

In the following specification, I have shown and described an interlocking feature in connection with my switch, whereby the operating pole is interlocked to the switch, except when the switch is in open or closed 80 position. This is secured by providing the locking mechanism with a key hole slot as shown, or by a variety of other constructions, and is for the purpose of preventing removal of the operating pole from the 85 switch when the latter is intermediate its open and closed positions.

However, I do not intend to be limited to the interlocking feature, as it will be apparent that the switch of my invention can 90 be employed without this interlocking action. If desired, the locking mechanism can be provided with a straight-sided slot which will have no interlocking action with the hook.

In the accompanying drawings I have illustrated two forms of my invention for single throw and double throw switches. I

do not intend to be limited to these particular embodiments, as my invention can be practised in a variety of different constructions.

5 Figure 1 is a side elevation of my invention applied to a single throw switch;

Fig. 2 is an end elevation of the same;

10 Fig. 3 is an enlarged fragmentary elevational view of the movable switch member showing the parts of the locking mechanism in detail;

Fig. 4 is a sectional view taken on the line 4-4 of Fig. 3;

15 Fig. 5 is a fragmentary plan view of the movable switch member and locking mechanism;

Fig. 6 is a side elevation of a modified form of locking switch;

20 Fig. 7 is an end elevational view of the same;

Fig. 8 is a sectional view through the movable switch member showing in detail the locking mechanism of the modified form; and

25 Fig. 9 is a perspective view of the operating hook on the end of the operating pole.

In Figs. 1 and 2, I have shown a sub-compartment type of switch. A post insulator 2 which supports the upper switch terminal 3 is mounted on the support 1. In this particular embodiment the terminal 3 is top connected through the insulator 2 by way of the stud 4 which extends through the center of the insulator 2 and has connection with the service above the panel 1. The lower end of the screw 4 has threaded or other engagement in a split socket in the curved end of the terminal 3-3, being clamped therein by bolts 5.

30 The lower end of the terminal 3 is bifurcated to provide two vertical hinge terminals 6 and 7 to which are hinged or pivoted the two pairs of blades 8-8' and 9-9' which constitute the movable switch member S.

45 The hinge and contact terminals with cooperating blades may be of any desired number from one to as many as are consistent with requirements. The hinge terminals 6 and 7 are interposed between the pairs of switch blades 8 and 9, pivotal connection therebetween being had by short bolts 11 provided with spring washers 12 which bear against the switch blade to retain them in firm frictional engagement with the terminals.

50 The pairs of switch blades 8 and 9 extend down in parallel alinement from the hinge arms 6 and 7 to the lower switch terminal 13. This lower switch terminal is mounted 60 upon the post insulator 14, which is secured upon a ledge or suitable support 15.

55 Similarly to the upper terminal 3, the lower terminal 13 is bottom-connected through the insulator 14 with the service and

has its end bifurcated to provide the two 65 lugs 17 and 18 which are adapted to engage between the pairs of switch blades 8 and 9, respectively, when the latter are in closed position.

The extreme ends of the pairs of switch 70 blades 8 and 9 are held together by short bolts 20 and co-operating spring washers 22.

As shown in Figs. 3 and 5, the lower terminal lugs 17 and 18 are provided with open slots 24 which receive the bolts 20 when the 75 switch is moved to closed position. A lock case or housing 25 is supported on the outer edge of the movable switch member S by ears 26 which extend down between the pair of switch blades 8 and 9 and are held therein 80 by shoulder pins 27 as shown in fragmentary section in Fig. 5. These pins have enlarged central portions 27', which act as spacers between the parallel switch blades. In the assembly of the switch the pins 27 are inserted 85 in the ears 26 and the pairs of switch blades 8 and 9 are placed over the reduced ends of the pins and are clamped thereto by the bolts 20. The spring washers 22 yieldingly press the adjacent switch blades toward the 90 spacer 27' and these are made of the proper thickness to give the adjacent blades a spacing slightly less than the thickness of the terminals 17 and 18. Thus, when the movable switch member S is moved into closed 95 position, the pairs of switch blades 8 and 9 will be spread slightly by the beveled edges 28 of the terminal lugs 17 and 18, and will have firm contact with the sides of the terminals under the tension of the spring washers 22.

The lock case 25 has a narrow portion 29 extending out from the top which incloses a lock operating arm 31.

Referring to Figs. 3 and 4, the outer end 105 of the arm 31 is formed with an elongated eye 32 which registers with the key hole slots 33 and 33' in opposite sides of the casing 29. The arm is bifurcated as shown in Fig. 4 to extend between the pairs of switch blades 110 8-8' and 9-9'. The inner ends of the arms 31 are pivotally mounted on the transverse shoulder pins 35 which are supported in the pairs of switch blades 8-8' and 9-9'.

115 In the description immediately following I shall refer only to the parts supported between the switch blades 8-8', it being understood that a duplicate combination of locking parts is disposed between the switch 120 blade 9 and 9'. The number of blades may be varied to suit conditions.

The upper edge of the terminal 17 is formed with a notch 36 (Fig. 3) in which engages the hook of the detent latch 38. 125 This latch is pivoted on the enlarged portion of the pin 35 between the switch blades 8 and 8'. A latch bolt 39 is supported be-

between the switch blades 8 and 8', and is guided for reciprocating movement by shoulder pins 40, which lie in slots in the bolt 39 as shown in dotted lines in Fig. 3. The lower end of the bolt 39 is scarfed, as is also the outer end of the latch 38, these two ends forming an overlapping connection substantially filling the space between the switch blades 8 and 8'. The end of a pin 41 extends through alined holes in the scarfed parts of the latch 38 and latch bolt 39.

The under face of the lock cover 25 is provided with an arcuate recess 43, directly over the space between the switch blades 8 and 8', to accommodate the transverse shoulders of the arm 31 in its oscillating movement.

Referring to the latch bolt 39, a compression spring 44 is confined between the end 20 of one of the slots therein and the companion pin 40, and tends to retain the nose 45 of the bolt in a notch 46 in the lower edge of the hinge arm 6. A circumferential cam 47 is formed in the lateral edge of the terminal 6, concentric with the bolt 11 and extends from the notch 46 to another notch 48 in the lateral edge of the terminal 6. This latter notch is angularly positioned approximately 90° from the notch 46 so that 30 when the movable switch member S is revolved up to a position at right angles to its closed position (as shown in dotted lines in Fig. 1) the nose 45 of the latch bolt will be engageable in the horizontal notch 48 to lock 35 the movable switch member S in this open position. The notches may be made for any angle desired.

It will be apparent that to release the locking mechanism the arm 31 must be oscillated 40 about the transverse pins 35. This motion swings the yoke 31, moving the latch 38 from the notch 36 and retracting the latch bolt 39 from the notch 46.

The operating handle H, for operating 45 the switch, is illustrated in Fig. 9. A cap member 50 is mounted upon the end of a pole 51 of wood or other insulating material. This cap member has a laterally extending shank 52, provided with an enlarged head 53, of proper diameter to pass through the circular opening of the key hole slot 33 but larger than the narrow end 50 of the slot. In the operation of the switch, the enlarged head 53 of the operating hook 55 H is inserted through the alining key hole slots 33 and the eye 32 in the casing 26. The operating pole is drawn in a line practically parallel to the movable switch S, drawing the shank 52 down into the narrow 60 end of the key hole slot 33 and simultaneously rocking the yoke 31. As previously described, the motion of the arm 31 is transmitted to the latch 38 and the latch bolt 39, disengaging the same from their re-

spective notches. The movable switch member S is now free to be swung into its open position shown in dotted lines in Fig. 1.

As soon as this motion begins, the operating hook is interlocked in the key hole slot 33. The head 53 on the hook prevents removal of the same through the constricted end of the key hole slot 33 and the latch 38 in its engagement with the upper edge of the terminal 17 prevents retrograde movement of the arm 31 to return the eye 32 to 70 coincidence with the circular opening in the key hole slot 33. This interlocked relation between the operating hook H and the movable switch member S is maintained until the switch member S has been revolved into 75 and is locked in open position. This is accomplished first by the sliding engagement of the hook end of the latch 38 along the upper edge 55 of the terminal 17, and secondly by the sliding engagement of the nose 85 45 along the circumferential cam 47, these two actions overlapping so that at no time during the operating movement of the switch member S will the yoke 31 be free to return to a position bringing the eye 32 90 into registration with the circular opening of the key hole slot 33.

When the switch member S has been moved to open position, the nose 45 of the bolt 39 rides off of the end of the cam 47 95 into the notch 48 under the action of the spring 44, locking the switch member S in this position. When the bolt 39 has been shot, the yoke 31 and the eye 32 return into registration with the circular opening of the 100 key hole slot 33, permitting withdrawal of the hook. The reverse operation will be obvious from the foregoing description. The release of the locking mechanism is accomplished by movement of the operating hook, 105 at an angle to the direction of the locked position of the switch member S and thus there is no difficulty in releasing the latching member from terminals.

In Figs. 6, 7 and 8 I have shown a modified form of locking mechanism which is particularly adapted to double throw switches. A panel 60 supports the post insulators 61 and 62, which in turn support the hinge terminal 63 and the contact terminal 64 of the switch. The hinge terminal 63 is shown as having front connection to the link 65, which is capable of assuming any angular position and the lower terminal 64 is shown as being back-connected 110 through the insulators 66. The manner of connecting these terminals is of course optional to meet the requirements of the installation. The switch blades 67-67' are hinged or pivoted to the terminal 63 by the 115 bolt and spring washer connection 68, and have their free ends held together by another such connection 69. Each of the par-

allel switch blades has riveted thereto an individual casing section 71-71'.

The casing sections 71-71' extend beyond the edges of the blades 67-67', with 5 a circular conformation to form lock casings and are provided with the oppositely extending key hole slots 72. The margins of these casings have inwardly extending flanges 73 (Fig. 8), the opposing flanges of 10 the two sections being adapted to register and form a casing.

The locking mechanism comprises the rocking arm 75, pivoted to the switch blades by the pin 76, and the two latch bolts 15 77-78. The upper bolt 77 is guided for reciprocating movement by the pins 80, secured in the switch blades 67 which operate in slots in the bolts 77.

The other bolt 78 is guided by a similar 20 pin 81 and the shank of the bolt 74 engaging in slots in this bolt. Compression springs 82-83 in these slots tend to retain the bolts in the positions illustrated. The arm 75 has lateral studs 84-85 which form 25 pins to the bolts 78 and 77, respectively. The ends of the arm 75 are provided with eyes 86-86 alined with the key hole slots 72 for engagement by the operating hook H in the operation of the switch.

30 The nose of the latch bolt 78 engages against a shoulder 87 in the edge of the switch terminal 64 and the nose of the latch bolt 77 engages against a shoulder 88 in the edge of the switch terminal 63. A cam surface 90, concentric with the bolt 68, extends 35 from the shoulder 88 in the terminal 63 to the notch or recess 91 cut into the outer end of the terminal. The cam 90 runs from the other side of the notch or recess 91 to the 40 shoulder 88 in the opposite edge of the terminal 63.

The operation of this modified locking switch is as follows:

The head 53 of the operating hook H is 45 inserted through the circular opening in either the right or left hand key hole slot 72.

The downward pull on the operating pole rocks the arm 75 and through the motion of the studs 84 and 85 retracts the latch bolts 50 77 and 78 from their respective shoulders 88 and 87. The switch is now unlocked and ready to be operated, which is accomplished as described for the preceding embodiment. When it is desired to lock the switch in open 55 position, the operating pole 31 is moved up until the latch bolt 77 comes into line with the notch or recess 91. The bolt will drop into the notch, due to the compression spring 82. The arm 75 will move so that the operating hook can be withdrawn through the 60 circular opening in the key hole slot 72.

When the switch is constructed as a double throw switch, an additional terminal 93, similar to the terminal 64, is supported upon

a post insulator 94 extending from the panel 60. Assuming that it is desired to complete the throw on the lower terminal 64 to the upper terminal 93, the operating pole 51 would be held with the operating hook thereof at the extreme narrow end of the 70 key hole slot 72. This would prevent the latch bolt 77 from snapping into the notch or recess 91 and accordingly the switch member S' could be carried over and into engagement with the switch terminal 93. When 75 the switch member S' has been moved into closed position upon either the terminal 93 or the terminal 64, the latch bolts 77 and 78 will snap back of the respective shoulders in the edges of the switch terminals, locking 80 the switch, and releasing the hook. The terminals 93 and 64 are provided with shoulders 95 (see upper terminal 93) on the sides of the terminals to limit the inward travel of the movable switch member S'. 85

The cams 90 afford the interlocking action between the switch member and operating hook. In the travel of the movable switch member S' from closed to opened position and vice versa, the latch bolt 77 is retained 90 in retracted position by these cams, and through the bolt 77 retain the arm 75 with the eye 86 adjacent the narrow end of the key hole slot 72. By the provision of two key hole slots 72, the locking mechanism is 95 always releasable by a downward pull of the operating hook H, irrespective of whether the switch member S' is in engagement with the terminal 93 or the terminal 64.

I do not intend to be limited to the particular details of construction shown and described. 100

I claim:

1. In an electrical switch, switch terminals, a switch member adapted to connect 105 said terminals, locking means on said switch member for locking the same in open or closed position, and an operating member engageable with said locking means to release the latter, said locking means being released by movement of the operating member substantially lengthwise with respect to 110 said switch member.

2. In an electrical switch, switch terminals, a switch member adapted to connect 115 said terminals, locking means for locking said switch member in open or closed position, an operating member engageable with said switch member for first releasing said locking means and subsequently operating 120 said switch member, said locking means being releasable by movement of said operating member substantially lengthwise with respect to said switch member.

3. In an electrical switch, switch terminals, a switch member adapted to connect 125 said terminals, locking means on said switch member for locking the same in open or

- closed position, and a device for operating said switch, said operating device engageable with said locking means to release the latter prior to movement of said switch member, movement of said operating device in releasing said locking means being angularly displaced to the subsequent movement of the operating device in moving the switch member.
- 10 4. In an electrical switch, switch terminals, a switch member adapted to connect said terminals, locking means for locking said switch member in open or closed position, a member for operating said switch, and means necessitating two distinct movements of said operating member for releasing said locking means and for actuating said switch.
- 15 5. In an electrical switch, switch terminals, a switch member adapted to connect said terminals, locking means on said switch member for locking the latter in open or closed position, a member for operating said switch, means necessitating two distinct movements of said operating member for first releasing said locking means and for subsequently actuating said switch, and means for interlocking said operating member to said locking means while said locking means is released.
- 20 6. In an electric switch, a plurality of switch terminals, a switch member movable to open and closed positions relative to said terminals, locking mechanism on said switch member for locking the latter in either of said positions, and lock releasing means on said switch member operable by movement of the same at an angle to the closing or opening movements of said switch member.
- 25 7. In an electric switch, a plurality of switch terminals, a switch member movable to open and closed positions relative to said terminals, locking mechanism on said switch member comprising latches engageable in recesses in said terminals to lock said switch member in either of said positions and a releasing arm operatively connected to said latches and operable by movement substantially parallel to the disengaging movement of said latches.
- 30 8. In an electric switch, a plurality of switch terminals, a switch member movable to open and closed positions relative to said terminals, locking members on said switch member engaging with said terminals to lock said switch member in either of said positions and a releasing arm operable to release said locking members by movement substantially parallel to the movement of said locking members.
- 35 9. In an electrical switch, switch terminals, a switch member adapted to connect said terminals, locking means for locking said switch member in closed position,
- means for operating said switch, and means necessitating two distinct movements of said operating means for releasing said locking means and for actuating said switch.
10. In an electric switch, a plurality of switch terminals, a movable switch member pivoted to one of said terminals, locking mechanism on said switch member for locking the latter in either open or closed position with respect to said other terminals, a releasing arm for said locking mechanism having an aperture therein adapted to be engaged by a switch operating device, said locking mechanism having a slot therein in registration with the aperture in said releasing arm and in which said operating device must be moved to actuate said releasing arm, said slot extending at an angle to the direction of motion of said switch member.
- 15 11. In a locking switch, a pair of parallel switch blades, locking mechanism between said switch blades, a lock releasing member extending transversely from said switch blades and having an aperture therein engageable by a switch operating hook, and a cover member secured to the free ends of said switch blades and inclosing said lock releasing member, said cover member having slots coincident with said aperture, said cover member connecting and holding said switch blades in parallel alinement.
- 20 12. In a locking switch, a plurality of parallel switch blades, locking mechanism between said switch blades, a lock releasing member extending transversely from said switch blades and having an aperture therein engageable by a switch operating hook, a cover member secured to the free ends of said switch blades and inclosing said lock releasing member, said cover member having key hole slots coincident with said aperture for interlocking said switch operating hook thereto, and lugs on said cover member extending between said switch blades for spacing and holding said blades in parallel alinement.
- 25 13. In combination, a switch blade, a pivot post for the blade, a gripping or contact post for the blade, a bolt for engaging one of the posts supported on the blade and being movable along the blade, and a lever pivoted to said blade and bolt transversely of the blade and of the bolt, said lever having an eye in its free end, whereby said bolt is released by movement at an angle to the operating movement of said blade.
- 30 14. In combination, a switch blade, a pivot post for the blade, a gripping or contact post for the blade, a bolt for engaging one of the posts supported on the blade and being movable along the blade, and a lever pivoted to said blade and bolt transversely of the blade and of the bolt, said lever hav-

ing an eye in its free end, and a casing guarding the free end of the lever, said casing being connected to the blade.

15. In combination, a switch blade, a pivot post for said blade, a gripping or contact post for said blade, latch means for engaging said gripping or contact post to lock said switch blade in closed position, latch

means for engaging said pivot post for locking said switch blade in open position, and 10 means for releasing said latch means.

In witness whereof, I hereunto subscribe my name this 4th day of January, A. D. 1918.

FRANK E. GETTS.
